UNITED STATES PATENT OFFICE.

GEORGE V. PADE AND CONRAD T. NEITZEL, OF DALLAS, TEXAS, ASSIGNEES TO AMERICAN ART NEEDLE COMPANY, OF DALLAS, TEXAS, A CORPORATION OF DELAWARE.

NEEDLE FOR HAND-EMBROIDERY AND SIMILAR WORK.

1,371,977.

Specification of Letters Patent. Patented Mar. 15, 1921.

Application filed October 20, 1919. Serial No. 331,923.

To all whom it may concern:

Be it known that we, GEORGE V. PADE and CONRAD T. NEITZEL, citizens of the United States, residing at Dallas, in the county of Dallas and State of Texas, have invented certain new and useful Improvements in Needles for Hand-Embroidery and Similar Work, of which the following is a specification.

10 This invention relates to certain new and useful improvements in embroidery needles, and the primary object of the invention is to provide a needle which is equipped with different sized points to permit the ready and quick detaching of one point, and the equally ready and quick attachment of a different sized point so as to adapt one needle or handle for various characters of embroidery or similar work.

15 The invention further aims to provide a point which has a novel character of fastening and which can also be used with the gage forming the subject matter of an application filed August 4, 1919, Serial No.

25 315,055.

In the drawings—

Figure 1, is a side elevation of the invention;

Fig. 2, is a bottom plan view;

30 Fig. 3, is a top plan view;

Fig. 4, is a section on line 4—4 of Fig. 1; and

Figs. 5 and 6 are sections on lines 5—5, and 6—6 respectively of Fig. 2.

35 In proceeding in accordance with the present invention, a hollow body 1, is formed to provide a substantially cylindrical handle having an attenuated frusto conical shank 2.

40 The side edges of the body and shank are spaced apart to provide a thread-receiving slit 3. The detachable point 4 is provided with a flared socket 5 located at the inner end thereof and formed to conformably engage over the frusto-conical shank 2. The socket and the point have their side edges spaced apart to form a thread receiving slit 6, which registers with the slit 3 of the body and shank.

45 50 A resilient spring arm 7 extends outwardly from socket 2 and has its outer end turned at right angles to provide a finger 8 which engages in a slot 9 formed in the body 1.

The gage 10 is of strip-like formation and like the arm of the needle point is formed of spring metal having a pair of spring gripping fingers 11 intermediate its ends which yieldingly embrace the handle 1, as depicted in Figs. 1 and 2. The forward end of the gage has an out-turned bifurcated or forked part 12 which straddles the needle point, while the opposite end is also turned outwardly to form a pawl 13 which is selectively received in any desired one of a series of transverse notches 14 formed in the handle.

The gage is thus adjustable to various positions determined by the range of the notches 14 and since it is disposed and operates over the socket and arm of the detachable point, it will be thus apparent that the latter is assisted in being held in place by the gage. To remove the point and apply a different sized point, it is necessary to first remove the gage, so as to permit the finger 8 of the point to be raised up out of notch 9, whereupon the point is moved forwardly to disengage its socket from the shank 2.

In applying the point, the finger 8 snaps into the notch 9, the end walls of the latter engaging the finger sides so as to prevent the needle socket from rotating. Since the gage overlies the finger 8, the latter cannot accidentally leave its notch 9.

What is claimed is:

1. In combination with an embroidery needle having a body provided with a substantially conical shank, and formed with a notch beyond the shank, a detachable point having a socket conformably receiving the shank and having a resilient arm the outer end of which is turned at right angles and engaged in the notch.

2. In combination with an embroidery needle having a body provided with a substantially conical shank, and formed with a notch beyond the shank, a detachable point having a socket conformably receiving the shank and means carried by the point and removably engaged in the notch to hold the socket in position on the shank.

In testimony whereof we have signed our names to this specification.

GEORGE V. PADE.
CONRAD T. NEITZEL.
